UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,587, dated August 28, 1894.

Application filed July 28, 1894. Serial No. 518,887. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of broad vertical stripes formed of lines and dots or balls 10 with serpentine or wavy lines running centrally through the stripes and forming oval-shaped panels containing sprays of flowers and leaves of roses and pinks, and a vertical row of oval-shaped panels formed of herring- 15 bone lines arranged between the vertical stripes as represented in the accompanying

drawing. A vertical line of small balls runs centrally through the oval-shaped panels. The border or upper portion of the design is formed of ornaments of vase-like form filled 20 with flowers and leaves of roses and pinks, and extend upwardly from the upper ends of the vertical stripes as shown in the drawing.

What I claim is—

The design for wall paper herein shown 25 and described.

Witness my hand this 26th day of July, 1894.

CHARLES BOOZE.
